UNITED STATES PATENT OFFICE.

LAURENCE N. NELSON, OF STURGEON BAY, WISCONSIN.

SAW-GUARD.

1,091,156.

Specification of Letters Patent. Patented Mar. 24, 1914.

Application filed August 16, 1912. Serial No. 715,500.

To all whom it may concern:

Be it known that I, LAURENCE N. NELSON, a citizen of the United States, residing at Sturgeon Bay, in the county of Door, State of Wisconsin, have invented certain new and useful Improvements in Saw Guards; and I do hereby declare the following to be a full, clear, and exact description of the invention, such as will enable others skilled in the art to which it appertains to make and use the same.

This invention relates to guards for rotary saws and has for an object to provide a guard that will be adjustable so as to permit of various sizes of timbers entering the guard to be operated upon by the saw.

A further object of the invention is to provide means for easily and quickly adjusting the guard to operative position.

With the above objects in view the invention consists of certain novel details of construction and combination of parts hereinafter fully described and claimed, it being understood that various modifications may be made in the minor details of construction within the scope of the appended claim.

In the accompanying drawings forming part of this specification:—Figure 1 is a side elevation of the device applied. Fig. 2 is a front elevation of the parts shown in Fig. 1. Fig. 3 is a cross sectional view taken through the parts of the guard shown in Fig. 1. Fig. 4 is a longitudinal sectional view through the parts shown in Fig. 2.

Referring now to the drawings in which like characters of reference designate similar parts, 10 designates the spaced longitudinal bed sills of the saw, upon which a carrier 11 slidably supports the timber to be operated upon, the rotary saw 12 being mounted upon a shaft 13 which is journaled for rotation in bearings 14 fixed to the bed sills. These parts are of ordinary construction and form no part of the present invention.

The saw guard is supported by a vertically disposed sheet metal standard 15 which is equipped with parallel vertical slots 16. A bed plate 18 is bolted or otherwise secured to one of the bed sills 10 and is equipped on the top face with angleirons 19 to which the lower edge of the standard is riveted as shown at 20 or otherwise secured. The top edge of the standard is

bent over toward the saw to provide a stop hook 21.

The guard hood comprises a pair of lower angleiron bars 22, which are of sufficient length to extend from the rear edge of the standard forwardly beyond the standard and over the saw, there being a pair of upper angleiron bars 23 arranged in the vertical plane of the lower bars and extending parallel therewith for a distance equal to the width of the standard, thence being bowed downwardly at their forward ends as shown at 24 and terminally secured to the forward ends of the lower bars. Both lower bars are connected terminally and also intermediate the ends by cross bars 25, and both upper bars are connected terminally and intermediate the ends by cross bars 26. A sheet metal back plate 27 is riveted or otherwise secured to the upper and lower bars next adjacent to the standard, and guide lugs 28 are arranged in vertical alinement in the back plate and extend through the guide slots 16 of the standard.

A wire mesh screen 29 is stretched over the skeleton frame above described and houses the saw, the screen extending over the top, bottom, end, outer side, and that portion of the inner side of the frame not occupied by the back plate. The hood may be moved vertically upon the standard through the instrumentality of the guide pin and slot connection between the standard and hood, and for thus actuating the hood the following mechanism is employed.

The back plate is provided on the lower edge with an inwardly projecting lip 30 which is equipped with an internally threaded bearing 31. A smooth bore bearing 32 is arranged on the bed plate in vertical alinement with the bearing 31. An upstanding feed screw 33 is journaled for rotation in the bearing 32 and threads through the bearing 31, actuation of this stand shaft serving to advance or retract the bearing 31 longitudinally of the feed screw with a resultant raising or lowering of the hood. A manually operable crank shaft 34 is journaled in suitable bearings 35 carried by one of the bed sills 10 and is equipped with a bevel gear 36 which meshes with a bevel gear 37 fixed on the lower end of the feed screw. Upon actuation of the crank shaft the feed screw will be rotated to raise or lower the

hood. The hood is braced against vibration by means of an inclined brace rod 37' secured to the plate 31 and to a cross bar 37" secured to the bed sills 10.

5 The stop hook 21 of the standard contacts with the adjacent upper bar 23 of the hood frame and limits raising movement of the frame, such contact taking place prior to the advance of the guide lugs to the upper 10 ends of the guide slots, thus obviating sheering off of the guide lugs by contact with the end walls of the slots.

What is claimed, is:—

15 The combination with a circular saw and its support, of a saw guard including a sheet metal plate secured to said support upon one side thereof parallel to said saw,

and having the top edge bent toward said saw to produce a stop flange, a hood over said saw slidably mounted on said plate and 20 adapted to engage with said flange whereby the movement of said hood away from said saw is limited, means on said plate engageable by said hood and serving to limit movement of said hood toward said saw, and 25 means for moving said hood toward and away from said saw.

In testimony whereof, I affix my signature, in presence of two witnesses.

LAURENCE N. NELSON.
